UNITED STATES PATENT OFFICE.

BRUCE CLARK WHITE, OF NEW YORK, N. Y., ASSIGNOR TO R. HOE AND CO., OF NEW YORK, N. Y., A CORPORATION OF NEW YORK.

PLATE CLAMP.

Application filed December 9, 1922. Serial No. 605,874.

To all whom it may concern:

Be it known that I, BRUCE CLARK WHITE, a citizen of the United States, residing at New York, county of New York, and 5 State of New York, have invented certain new and useful Improvements in Plate Clamps, fully described and represented in the following specification and the accompanying drawings, forming a part 10 of the same.

My invention relates to plate clamping mechanism for rotary printing presses and its object is to provide clamping mechanism for holding printing plates upon the plate 15 cylinder which can be operated quickly and easily by a single operation and cannot become loose after it is once tightened and will be sufficiently yielding in its grip upon the edges of the plates to insure the holding 20 of the plates at several points even though the plates vary slightly in size or form.

Another object of my invention is to provide a wrench for operating the clamping mechanism so constructed that it can be applied or removed only at the extreme limits 25 of the movement of the clamping device, when the clamps are either full open or properly locked upon the plates.

A further object of my invention is to so 30 arrange the mechanism that the wrench will be out of the way of the plate and operator when the clamps are open, but will be in his way when the plates are locked and until the wrench is removed.

35 Further objects of my invention are to provide for clamping or releasing the inner or middle plates when outer plates are absent, as is sometimes the case in cylinders arranged for 4 plates abreast, when printing 40 the middle pages only.

It has been common practice heretofore to force the clamps against the plates by screws, operated by a wrench or ratchet. These devices are slow in action and have a 45 fixed rate of movement of the clamps corresponding with the wrench movement. If more than one screw is employed for each plate, they must be intergeared. Other forms of plate clamping devices have been 50 employed, each lacking, however, in some important particular, such as leverage, power, convenience, quickness or safety. The object of my invention is to provide a plate clamping device which shall embody in the 55 simplest form all of the features which are

essential or desirable in such a mechanism.

In the accompanying drawings which illustrate my invention,—Fig. 1 is a plan view of a part of one plate cylinder, with my plate clamping device attached thereto. 60 Fig. 2 is a vertical section of same on line 1—1 of Fig. 3. Fig. 3 is an end elevation. Fig. 4 is an enlarged detail section on line 2—2 of Fig. 5. Fig. 5 is a part plan and a part sectional view on line 3—3 of Fig. 4. 65 Figs. 6 and 7 are detailed views of the end of the wrench. Figs. 8 and 9 are detailed views of the springs. Fig. 10 is a plan view of a modification of my clamping device adapted to plates of a predetermined width. 70 Fig. 11 is a vertical section of same on line 4—4 of Fig. 12. Fig. 12 is an end elevation of same.

Referring to the drawings, 10 indicates a plate cylinder of the usual form, provided with a shaft 11. The cylinder is provided with a plurality of slots 12, extending a suitable distance into the cylinder longitudinally thereof, in which are slidably mounted plate clamps 13 which are of the usual 75 construction and are adapted to engage the outer bevelled edges of the printing plate 14 in a manner to retain said plate upon said cylinder when the clamps are forced against it. 80

At the outer ends of the slots 12 are sliding blocks 15 slidably mounted in said slots. Both the plate clamps 13 and the sliding blocks 15 are internally threaded to engage 85 threaded portions of the rods 16, one end of which has a right-hand thread and the other end a left-hand thread. A portion 17 of each of these rods is of square or hexagonal section whereby it may be turned by a suitable wrench to adjust the distance between 90 the plate clamp 13 and the corresponding sliding block 15 as desired.

Each sliding block 15 is provided with a projecting part 18 preferably made integral with the sliding block and cylindrical form 100 and preferably provided with an antifriction roller 19.

The rollers 19 fit freely in diagonal cam slots 20 formed in the curved cam segment 21, which latter is fitted to rotate upon the hub 22 of the cylinder 10 through a short arc of angular movement. The cam segment 21 is limited in longitudinal movement between the shoulder 23 of the cylinder 10 and the collar 24, which latter is preferably 105 110

made in halves for convenience in assembling and is secured to the cylinder hub by screws 25.

Provision is made for a slight longitudinal movement of the cam segment 21, which movement is resisted by springs 26, preferably one being provided in line with each sliding block 15. Each spring is placed in a suitable pocket 27 in the collar 24. The 10 said collar preferably extends into an annular recess 28 formed in the cam segment 21. By this arrangement the springs are enclosed and are retained in their pockets. The springs are formed with the proper curvature to cause them each to bear at their middle point against the cam segment 21 and at each end against the collar 24 with such initial pressure as may be desired for frictional resistance against the angular 15 movement of the cam segment 21. The longitudinal movement of the said cam segment away from the plate 14 when the clamps are forced against the plate will cause the springs to straighten and react 20 with such resistance as may be desired at the time of final pressure.

The cam slots 20 are preferably formed in a diagonal direction, as shown at 29, which diagonal direction gradually changes into 25 a curved path at 30 of lessening angularity until at the end of the groove it is practically at right angles to the longitudinal axis of the cylinder 10.

The resultant longitudinal movement of 30 the sliding blocks 15 toward the plate will be at first relatively fast as the cam segment is moved from its extreme right hand position toward the left, Fig. 1. As the plate clamps 13 meet the plate 14 the sliding blocks move inward more slowly and with increasing leverage and force until their inward movement ceases and the leverage is multiplied greatly. At the final position the springs 26 are stressed more or less according to the inequalities in the plates. By adjusting the right and left hand screws 16 the whole or any part of the spring tension may be applied to the plate clamps as desired.

To operate the cam segment 21 through the required arc of movement I preferably use a crank arm 31 whose shaft 32 is rotably journaled in a hole in the end of the cylinder 10. The said crank is provided 35 with a crank pin 33 preferably mounted with an anti-friction roller 34. The hub of the crank arm is preferably square at 36 and has projecting flanges formed upon it at 36. An open-end wrench 37 is fitted 40 to slide freely onto the squared portion 35 of the said crank arm between the flanges 36 and the end wall of the cylinder 10. The wrench 37 is provided with projecting lugs 38, preferably on both sides. Grooves 39 45 formed in the end wall of the cylinder 10

extend from the periphery of the said cylinder radially toward the center of shaft 32 of the crank arm 31. An annular recess or counterbore 40 provides clearance for the lugs 38 when the wrench is moved 70 through its arc, which movement is limited by stop pins 41 in each direction. These parts are so arranged that the wrench can be slipped onto the square of the crank only when the center line of the crank arm 31 75 and one of the grooves 39 coincide and obviously the wrench 37 can be removed only in these positions. Any angular movement of the wrench when it is on the said crank arm, from either of its extreme positions, locks the wrench and prevents its removal until it has completed its movement in either direction.

The crank pin roller 34 is fitted to move freely in a groove or recess 42 extending 80 across the inner face of the cam segment 21. This groove is inclined from a radial line sufficiently to form a right angle with the crank arm 31 when the latter is at the extreme limit of its movement to the left (see Fig. 90 4) corresponding with the position of the parts at the time of final pressure of the plate clamps 13 against the plate. This arrangement results in the slowest movement of the cam segment relative to the angular movement of the wrench at the time of greatest pressure upon the plate 14 and consequently the greatest leverage of the wrench at this time.

The leverage of the wrench over the plate 95 clamp is therefore a multiple of the two cam leverages, both of which are practically infinite at the end of the pressure stroke. To provide for clearance for the crank arm 31 and wrench 37 it is necessary 100 to cut recesses 43 in the cam segment 21.

The dotted line 44 indicates the position 105 of the wrench when the clamps are open. The wrench 37 is then out of the way of the operator. The dotted line 45 indicates the 110 position of the wrench when the plates are locked up. The wrench in the latter position is in the way of the operator and he must remove it to get out from the operating space between the cylinders. This arrangement assures the removal of the wrench 115 before starting the press. The wrench may be left on in position 44 while changing plates.

Double clamps 46 are fitted to slide freely 120 in the slots 12 of the cylinder 10 when two plates are placed end to end along the cylinder each way from the center. These clamps 46 are each provided with a spacer bar 47. A head 48 is screwed onto the said spacer bar and may be adjusted thereon as desired. The spacer bar 47 is fitted to slide 125 freely in the bearing block 49.

When the outer plate 14 is not used, the 130 inner plate may be clamped by adjusting

the plate clamp 13 inward by the screw 16 until it contacts with the head 46 when its movement, through the cam movement of the sliding block 15, will cause the inner plate to be clamped by the double clamp 46. The purpose of the adjustable head 48 is to permit of an adjustment of the distance necessary to move the plate clamp 13 to effect the clamping of the inner plate, whatever the width of plates may be. Thus the minimum of adjustment is required for a change from full width of web to half web or "dinkey" sheet, when the latter is run on middle pages. Likewise all of the parts are available for a change from 8 to 10 columns, and either width may be run with equal economy of time in plate changing and lock-up.

Referring now to Figs. 10, 11 and 12 the device shown therein is of the same character and principle of operation as that already described except that the clamps 50 are operated directly by the cam segment 21 without the adjustable connections 16 and sliding blocks 15. This type of clamp is adapted to plates of a predetermined width in which but little, if any, adjustment of the clamps is required. A modified form of abutment collar 51 is shown, secured to the cylinder by bolts 52 screwed into the end wall of the cylinder. The collar is made preferably slightly yielding longitudinally by providing springs 53 between the heads of the bolts 52 and the collar 51. These springs are preferably of the dished washer type. They serve the same purpose as the springs 26 of the device first described.

The inner plate clamps 46 are forced against the inner plate 14 by the rods 54 which are screw threaded through the outer clamp 50, and extend through the inner clamps 46 and are provided each with a collar 55 and nuts 56. When the outer plate 14 is absent a few turns of the screw 54 will bring their collars 55 against the inner clamps 46 in a manner to utilize the plate lock-up device for locking up the inner plates in the same manner as for the outer plates.

When it is desired to open the clamps and release the printing plates, a movement of the cam segment ring 21 to the right moves the clamps 50 away from the outer plate 14 and at the same time pulls the clamps 46 away from the inner plate 14. The relative opening movements of the two sets of clamps 46 and 50 is such as to permit both inner and outer plates 14 to be removed clear of the clamps, and is effected by one movement of the operating wrench, which acts with sufficient leverage and power to positively withdraw the two sets of plate clamps against their tendency to stick fast in their grooves.

It will be understood that the device shown is for a single lock-up device. It will be duplicated upon the other half of the cylinder and a pair of lock-ups will be used ordinarily at each end of the cylinder. It is obvious, however, that without departing from my invention, a plate cylinder might be used of such circumference as to carry more than two plates around its circumference or more or less than four plates abreast. It is also obvious that the number of plate clamps along the margin of a plate is not limited to three, as shown, but may be more or less. Also that space, dimensions and other circumstances may modify the details without changing the principle of the invention.

What I claim as my invention and desire to secure by Letters Patent, is,—

1. The combination with a plate cylinder and plate clamps and blocks slidingly mounted thereon and movable longitudinally thereof; unyielding lengthwise adjustable connections between said plate clamps and said blocks; means for moving said blocks longitudinally and a yielding resistance to said moving means independent of the clamp or block.

2. The combination with a longitudinally grooved plate cylinder and plate clamps and blocks both longitudinally movable in the grooves of said cylinder and unyielding adjustable connections between said plate clamps and blocks, of yielding elements on said cylinder, and clamp actuating means between said yielding elements and said movable blocks.

3. The combination of a plate cylinder, a printing plate thereon, longitudinal grooves in said cylinder, plate holding clamps longitudinally movable in said grooves, blocks likewise movable in said grooves, unyielding adjustable connections between said clamps and blocks and means for moving said blocks, comprising a peripherally movable curved segment having diagonal grooves adapted to engage said blocks, and means for actuating the said segment.

4. The combination of a longitudinally plate holding cylinder having plate clamps and blocks both longitudinally movable in the cylinder grooves, said clamps and blocks being adjustably and unyieldingly connected, a diagonally grooved peripherally movable segment for actuating the said blocks and plate clamps; a shoulder upon said cylinder and yielding elements between said shoulder and said segment to limit the longitudinal pressure thereon and means for actuating the segment.

5. The combination of a plate holding cylinder having longitudinally movable diagonally grooved segment for moving the plate clamps longitudinally and means for moving the segment comprising a slot across

said segment, and a crank arm, the crank pin of which engages said slot, and means for actuating said crank arm.

6. The combination of a plate cylinder, a plate thereon, plate clamps mounted on the cylinder, a peripherally movable segment for moving the plate clamps, a crank arm journalled in said cylinder, a crank pin on said crank arm engaging a slot in said segment, the said slot being tangent to the path of travel of said crank pin when the latter is at the limit of its throw in the direction to bring the said plate clamps into clamping engagement with the said plate.

15 7. The combination of a plate holding cylinder having longitudinally movable plate clamps, a peripherally movable segment arranged to move the plate clamps longitudinally in either direction, a slot or recess in the segment engaged by a crank arm and means for moving said crank arm comprising a removable hand operated wrench actuated through a portion of a revolution only.

25 8. The combination of a plate holding cylinder having longitudinally movable plate clamps, means for moving said plate clamps, said means including a crank arm movable through a portion of a revolution only, a squared place upon said crank arm, a wrench engaging said squared place, a flange on said crank arm to confine said wrench to said squared portion, a projection on the side of said wrench, radial channels or grooves corresponding with the limits of throw of the crank arm, arranged to admit the wrench to the crank arm when the latter is at either limit of its throw and an annular groove to permit the crank arm to be turned between the limits of its throw when the wrench is in operative position on the crank arm.

35 9. The combination of a plate holding cylinder having longitudinally movable plate clamps, means for moving said plate clamps, including a crank arm adapted to receive a wrench in one longitudinal position only, and elements on said wrench registering with elements on said cylinder to permit the operative engagement of said wrench with said crank arm at either end of its throw and to retain said wrench upon said crank arm at intermediate positions between the ends of its throw.

55 10. The combination of a plate holding cylinder having longitudinally movable plate clamps, means for moving said plate clamps, including a crank arm actuated by a wrench through a portion only of a revolution and stop pins to limit the throw of the crank arm.

60 11. The combination in a printing press of a plate holding cylinder having longitudinally movable plate clamps, means for moving the clamps including a wrench, mov-

able through a portion of a revolution to lock or unlock the plate on the cylinder, and stops for causing the wrench when moved to locking position to extend sidewise of the cylinder and block access therewith.

70 12. The combination in a printing press of a plate holding cylinder having longitudinally movable plate clamps, means for moving the clamps including a wrench, movable through a portion of a revolution to lock or unlock the plate on the cylinder, and stops for either position of the wrench, said stops causing the wrench to extend above the cylinder and out of the way when in unlocked position or sidewise of the cylinder when in locked position so as to bar access therewith.

75 13. The combination in a plate holding cylinder having longitudinally movable plate clamps, of a cam plate for moving the clamps, a plate spring between the cam plate and the clamps, and cam operating means for actuating the cam plate.

80 14. The combination with a plate cylinder and plate clamps slidably mounted thereon and movable longitudinally thereof, of blocks also mounted thereon and movable longitudinally thereof, right and left hand screw connections between said plate clamps and said blocks and means for moving said blocks.

85 15. The combination of a plate cylinder, a printing plate thereon, a plurality of longitudinal grooves for each plate, a plate holding clamp in each groove, a sliding block at the outer end of each groove, a right and left hand screw connection between each plate clamp and its corresponding sliding block and means for moving said blocks simultaneously, longitudinally in said grooves comprising a peripherally movable curved segment, having diagonal cam grooves formed in it, one for each sliding block, a roller on each block for engaging both walls of the diagonal groove and means for moving the segment peripherally in both directions to effect a longitudinal movement of the sliding blocks in either direction.

90 16. The combination in a plate holding cylinder having a longitudinally movable plate clamp and means for moving it to clamp the outer margin of an outer or end plate on said cylinder, of a freely movable intermediate plate clamp to clamp the outer margin of an inner or middle plate on said cylinder, and means for operating said intermediate plate clamp comprising rods screw-threaded through one of said plate clamps and extending to engage the other of said plate clamps.

110 17. The combination in a plate holding cylinder having longitudinally movable plate clamps, of clamp blocks, a cam plate for moving the clamps, a plate spring between the cam plate and the blocks, and cam

operated means for actuating the cam plate. 18. The combination in a plate cylinder, of outer and inner sliding clamps for clamping outer and inner plates on the cylinder, 5 means for moving the outer clamp longitudinally away from the outer plate and connections from said moving means engaging the inner face of the inner clamp for positively moving the inner clamp longitudinally away from the inner plate.

19. The combination in a plate holding cylinder having longitudinally movable

plate clamps, of a cam plate for moving the clamps and cam operated means for actuating the cam plate.

20. The combination in a plate holding cylinder having longitudinally movable plate clamps, of a cam plate for moving the clamps, a yielding resistance between the cam plate and the clamps, and cam operated 20 means for actuating the cam plate.

In testimony whereof, I have hereunto set my hand.

BRUCE CLARK WHITE.
